**SELECTOR ARRANGEMENT FOR INDICATING
THE LOCATION OF ELEVATOR CARS**
William Frank Glaser, Eastchester, N.Y., and Arthur
Ennis Prince, Succasunna, N.J., assignors to Otis Ele-
vator Company, New York, N.Y., a corporation of
New Jersey

Filed Apr. 16, 1962, Ser. No. 187,896
16 Claims. (Cl. 340—21)

This invention relates to elevator control systems.

More particularly, it is concerned with the production at some remote location of an accurate representation of the physical location of the elevator car as it traverses its hoistway and the utilization of this representation in the control of the elevator.

In the elevator art it is usual to provide means for registering calls for the service of the car and to co-ordinate the location of the car with all such calls registered in order to cause the car to travel in an orderly fashion to floors to which passengers wish to be taken and to pass without stopping those intervening floors for which no service demand then exists. Such action requires that there be available an accurate representation of the car's location in its hoistway. Various types of machines, frequently called floor selectors, have been employed to produce this representation of the physical location of the car. Some of these have used a crosshead that is moved in synchronism with car movement to carry contacting brushes into contact with electric circuit terminals that are located at levels corresponding to the building landings. These terminals are activated or not in accordance with the requirements for service. Still others have used metallic strips or vanes mounted in the hoistway at positions corresponding to the various landings and magnetically actuated switches mounted on the car to be actuated as car movement brings a switch into contiguous relationship with one or another such vane. A variety of arrangements of this latter type are known, one such being disclosed in U.S. Patent 2,875,853, issued March 3, 1959, to Joseph H. Borden.

Generally speaking, arrangements of the former type are relatively costly machines whereas those of the latter type offer certain economies of cost which make them especially attractive for certain types of elevator systems. These latter types, however, have been found to be subject to malfunctioning for a variety of reasons with the result that they not uncommonly give a false indication of the cars' locations. Also, they are susceptible to calls registered while the car is adjacent the calling floor but having progressed too far to stop at that floor. Under such circumstances a false stop may be made at the next adjacent floor.

It is therefore an object of this invention to make possible the production of an indication of the car position in such manner that it may be utilized with the signal and control apparatus for controlling the movements of the car through a mechanism of relatively simple and economical design.

It is a further object of this invention to achieve the foregoing objective through the use of an arrangement that is virtually foolproof against malfunctioning under all commonly encountered conditions.

In one embodiment of the invention, which will be described herein, paired metallic vanes are employed near each landing intermediate the two terminal landings. These are used not only to produce an indication of the car's position, but also to initiate the action by which a car is stopped at a floor landing. To effect this latter function, the distance of the vane from its landing is co-ordinated with the speed of the elevator with which it is to be used. As a result, a single uniform length of vane will accommodate a wide range of elevator speeds, while

2

still providing an unvarying distance for slowdown and stopping which distance is appropriate for the speed of the individual elevator with which it is to be used. Thus, different operating speeds no not require use of different length vanes.

In this embodiment to be described it will be noted that the same inductor switch is used for both directions of car travel in an arrangement utilizing two such switches, each of which is activated at alternate floors. This makes possible, among other desirable achievements, the avoidance of a false stop at a floor next to the one from which the car is departing when a call is registered at that latter floor at the time the car is near it, which phenomenon has characterized most if not all previously known arrangements of this type employing inductor switches.

These and other advantages will be apparent from the following description of a preferred embodiment of the invention when read in conjunction with reference to the accompanying drawing, in which:

20 FIGURE 1 is a diagrammatic representation of an elevator system in which the staggered relation of the hatchway vanes at adjacent floors is shown;

25 FIGURE 2 shows in schematic form the essential portions of a simplified elevator control circuit including the call registration and direction control circuits; and

FIGURE 3 shows schematically the relationship of the elements of the inductor switch controlled relay stepping arrangement for producing a remote indication of the location of the car in the hoistway.

30 The invention will be explained in connection with the essential parts of a control system which would be suitable for use in a simplified type of elevator such as a single speed selective collective system. In this explanation reference will be made only to those parts of the control system that are necessary for producing a representation of the car's location and for co-ordinating that representation with car and landing calls in such manner as to control properly the car movements. It is to be understood that the actuation of the motor control circuits to effect the starting and stopping of the elevator is to be accomplished in any suitable manner, a number of which are well known in the art. In accordance with this plan to simplify the explanation of this embodiment, those circuits associated with the control of the doors, the leveling operation, bypass operation and for other conventional operating functions which have no specific connection with the invention here disclosed will be omitted.

40 In the accompanying drawing letter designations have been shown with the representation of the coil of particular switches and relays. Also, these same letter designations together with appended numerical designations have been indicated for the relay or switch contacts that are operated in response to energization of the respective coil. These designations are associated with switches or relays performing circuit operations as indicated below.

1C, 2C, 3C, etc. -----	Car-call relay*
2U, 2D, 3U, 3D, etc. -----	Hall call relay*
D -----	Down-direction switch
E -----	Inductor switch for "even" floors
EV -----	"Even" floor relay
1FL, 2FL, 3FL, etc. -----	Floor position relays*
NT -----	Loading time relay
O -----	Inductor switch for "odd" floors
OD -----	"Odd" floor relay
S -----	Starting switch (operate coil)
SR -----	Starting switch (release coil)
U -----	Up-direction switch
XD -----	Auxiliary down-direction relay
XU -----	Auxiliary up-direction relay
Z -----	Zone relay*

Relays designated with an asterisk (*) are of the latching type. The starting switch is a double coil relay having an operate coil and a release coil.

Referring now to the drawings it will be noted from FIGURE 1 that a hoisting machine having a rotating sheave 103 supports a car 101 and its counterweight 104 on hoist ropes 105 to serve a building which, for purposes of explanation, has been shown as having four landings. Call registering fixtures are provided at each landing, there being "up" and "down" call buttons 2SU, 2SD, etc. at the intermediate landings and single buttons 1SU and 1SD at the bottom and top landings, respectively. Car call buttons 1SC etc. are provided in the car. Inductor switch assemblies 99(O), 100(E) are mounted in any suitable manner on the exterior of the car in positions of vertical alignment with suitable vanes 12, 12A, 12B, etc. which are mounted in the hoistway at positions to associate closely with the inductors 99, 100 as the car approaches a landing. That is to say, each vane is located at a predetermined position both vertically and laterally. In the lateral sense it is so located that it comes into fairly close association with the face of the inductor as the car approaches the landing. In the vertical sense, the position of the edge of a predetermined vane is coordinated with the speed of the elevator such that the car platform is the desired "stopping distance" from the landing as the inductor leaves said vane edge. This correlation between car speed and vane location is desirable as it permits the use of vanes of uniform length for a variety of car speeds and stopping distances. Terminal limit switches 1L and 4L are mounted in the hoistway in positions to be actuated by cam 102 mounted on the side of car 101 as the car nears the terminals.

At this time it should be noted that the vanes 12 to 12E are arranged in two vertical columns. Vanes 12, 12C and 12D associated with the "odd" floors (lower terminal and third landing, respectively), are in one column and serve to actuate "odd" floor inductor 99. Vanes 12A, 12B and 12E associated with the "even" floors (second landing and top terminal, respectively) are in another column and serve to actuate inductor 100. As will be explained shortly, this two-column arrangement acts to prevent the presentation of a false indication of car location in the event of a momentary power failure or other happenings such as have caused false indications in earlier systems using only a single row of vanes for one direction of travel.

In the following explanation in which reference will be made to FIGURES 2 and 3, it will be understood that the relay contacts are shown for the de-energized condition of the relay coil in the case of single coil relays, and in the case of latching type relays the contact position corresponds to the reset condition. In the case of the start switch having an operate coil "S" and a release coil "SR," the contact positions correspond to the release coil having been the last energized.

In this explanation it will be assumed that the elevator is standing at the lower terminal (first floor). In this position it has actuated limit switch 1L by cam 102 to close contacts 1L1 in the circuit of operate coil 1FL of the floor position relay for the first floor and to open contacts 1L2 in the circuit of coil D of the down-direction switch. Contacts 1L1 in closing caused the first floor position relay to assume its operated or "set" position, opening its contacts 1FL1 in the circuit of coil XD of the auxiliary "down" direction switch and closing its contacts 1FL2 in the circuit of coil 2FL, contacts 1FL3 in the circuit of reset coil 1r of the first floor position relay, and contacts 1FL4 in the circuit of the reset coils of the first floor landing and car call registration relays.

Assume now that an intending passenger at the second landing registers an "up" call by pushing button 2SU and an intending passenger at the third landing registers a "down" call by pushing button 3SD. These actions cause the operate coils 2U and 3D, as the case may be, to be-

come energized by circuits extending from the positive (+) main through line 10, contacts 2SU or 3SD, coils 2U or 3D of the hall call registering relays and line 10a or 10b and 11 to the negative (-) main. Second floor up hall call relay closes its contacts 2U1 in the circuit of reset coil 2U of the up hall call relay and 2U3 in the circuit of lamp L2 without immediate effect. Contacts 2U2 in the direction determining circuit are also closed to cause energization of coil XU of the auxiliary "up" direction relay from the positive (+) main through closed contacts NT2, lines 16 and 17, contacts 2U2, 2FL5, 3FL1, 4FL1, coil XU, and closed contacts D3, XD1 and 4L2 to the negative (-) main. Third floor down hall call relay closes its contacts 3D1, 3D2 and 3D3 without immediate effect. The auxiliary "up" direction relay closes its contacts XU8, paralleling contacts NT2 as a holding circuit, and causes energization of operate coil S of the starting switch through contacts XU1. Contacts XU2 close in the circuit of coil U of the "up" direction switch without immediate effect. Operate coil S is energized through the circuit from positive (+) main through line 21, contacts XU1, NT1, line 22, coil S to the negative (-) main. The starting switch closes its contacts S1 in the circuit of coil S to establish a holding circuit, contacts S2 in the circuit of coil U of the "up" direction switch and contacts S4 and S5 in the circuits of lamps L2 and L3. These latter two are ineffective at this time. In addition, contacts S3 are opened (without effect) in the call reset circuit.

Coil U is energized from the positive (+) main through line 24, contacts S2, XU2, line 25, coil U, line 26, and contacts D3, XD1 and 4L2 to the negative (-) main. The "up" direction switch causes movement of the car by actuating the hoisting motor and releasing the brake in any convenient conventional manner. This control action is not part of the subject invention, is well known and is not to be described herein for purposes of brevity. In addition, contacts U1 in the circuit of coil NT of the loading time relay are closed to energize that coil and to charge capacitor 32 through its connected resistor; contacts U2 in the circuit of coil U close to prepare a holding circuit for that coil after car movement causes actuation of the "even" or "odd" floor relays; contacts U3 open in the circuit of "down" direction switch coil D to prevent "down" direction of travel until "up" travel is completed and in the car and landing call reset circuits contacts U4 open without immediate effect.

As the car moves upward from the lower terminal "odd" inductor 99 coacts with vane 12 to cause closing of "odd" contacts 36-40, but this is ineffective because contacts Z4 of the zone relay are separated, the relay having been reset when the car previously approached the terminal.

Upon further car movement the "even" floor inductor 100 coacts with vane 12A, as it meets its lower edge. This causes "even" contacts 36'-40' to close and through now closed contacts Z1 to energize coil EV of the "even" floor relay. This relay closes its contacts EV2 to be effective as a holding circuit for coil EV after the closing of contacts EV1 in the circuit of coil Z of the zone relay causes that coil to be energized to open contacts Z1 in parallel with contacts EV2. In addition, the zone relay closes contacts Z2 in circuit with coil 1r to cause resetting or unlatching of first floor position relay, opens contact Z3 in the circuits of reset coils 2r and 4r of the floor position relays; closes contacts Z4 to prepare a circuit for the eventual energization of operate coil OD of the "odd" floor relay and close contacts Z5 in the circuit of reset coil Zr of the zone relay to be energized at the next "odd" floor position. Contacts EV3 are also closed in the circuit of reset coil SR of the starting switch to prepare a circuit for the energization of this coil and resetting of that switch. Contacts EV4 in circuit with coil U of the "up" direction switch are closed to hold the "up" direction switch operated for the time that the

vane 12A and inductor 100 are in co-operative position. Simultaneously with the closing of "even" contacts 36'-40', coil 2FL of the second floor position relay is energized through the circuit including contacts 36'-40', XU3, 1FL2 and coil 2FL. This causes contacts 2FL1 to open and contacts 2FL2 and 2FL3 to close without immediate effect. Also, contacts 2FL4 in the hall and car call reset circuit are closed to cause the release of the starting switch by energizing coil SR through the circuit including closed contacts EV3, 2FL4, XD6, 2U1 and reset coil 2U of the second floor "up" hall call registering relay. The starting switch in releasing causes the holding circuit for coil S to be opened at contacts S1, contacts S2 in the circuit of coil U to be opened without immediate effect and contacts S3 in the call reset circuit to be closed completing a circuit for energizing reset coil 2U through resistor R1, line 41a, contacts EV3, 2FL4, XD6, 2U1 and coil 2U to cancel the second floor "up" hall call.

As continued car movement causes disassociation of inductor 100 and vane 12A at the upper edge of the vane, contacts 36'-40' are separated opening the circuits through coil 2FL (without immediate effect) and coil EV of the "even" floor relay to initiate the actual stopping operation. The "even" floor relay opens contacts EV1 in the circuit of coil Z, contacts EV2 in its holding circuit, contacts EV3 in the call reset circuit and contacts EV4 in circuit with coil U of the "up" direction switch. The de-energization of coil U brings about the actual stopping operation as it causes opening of the contacts in the motor control and brake circuits (not shown) in the conventional manner. In addition, contacts U1 separate in the circuit of coil NT to cause the "timing" of the loading time relay to be started by the discharge of the energy stored in capacitor 32 through its connected resistor and coil NT. As is well understood, this "timing" determines the interval the car will remain at the floor. Contacts U2 open in the circuit of coil U to cease their holding function and contacts U4 close in the call reset circuit to cancel any "up" hall call that may have been registered at the second floor after the car stopping sequence was initiated and the previously described call reset operation was completed.

Following upon the discharge of capacitor 32 through coil NT to a point where that coil is no longer energized in excess of its "drop-out" value the loading time relay releases, reengaging its contacts NT1 in the circuit of operate coil S of the starting switch. It also reengages its contacts NT2 in the direction control circuit but this is without effect as coil XU had remained energized through contacts XU8, 3D2, 3FL5, 4FL1, coil XU, contacts D3, XD1 and 4L2. Coil S is reenergized through line 21, contacts XU1 and NT1, as before, to cause self-holding contacts S1 to close as well as contacts S2 in circuit with coil U of the "up" direction switch. This completes a circuit for coil U through contacts S2, XU2, coil U, contacts D3, XD1 and 4L2 to cause restart of the car upwardly in the conventional manner.

If no further calls were registered the car would proceed to the third landing to pick up the "down" call there, however, let us assume that the second floor passenger upon entering pressed car button TSC for the top terminal, thereby energizing the operate coil TC to close contacts TC1 in the top floor car call reset coil circuit and contacts TC2 in circuit with coil XU in the direction determining circuit.

As the car proceeds upwardly from the second landing its inductor 100 meets vane 12B to cause closing of "even" contacts 36'-40' without effect since the zone relay is in the set position at this time and the car is leaving an "even" floor. Continued movement brings inductor 99 near vane 12C for the third floor at which a "down" call is registered. As the inductor and vane assume their effective positions, "odd" contacts 36'-40' are closed to cause energization of coils OD, 3FL and Zr.

Coil OD is energized through now closed contacts Z4 and causes its holding contacts OD1 to engage. Contacts OD2 are closed in circuit with closed contacts Z5 and causes coil Zr to be energized and unlatch or reset the zone relay. Contacts OD3 are closed (without immediate effect) in the call reset circuit and contacts OD4 are closed in circuit with coil U to establish a holding circuit through closed contacts U2. Contacts OD5 in circuit with lamp L3 are opened. The purpose of this circuit will be explained subsequently.

Simultaneously with the closing of "odd" contacts 36'-40', operate coil 3FL of the third floor position relay is energized through these contacts and contacts XU4 and 2FL2. This causes opening of contacts 3FL1 and 3FL5 in the direction determining circuit without effect as coil XU is maintained energized through closed contacts TC2. Contacts 3FL2 in circuit with coil 2FL are closed (without effect), as are contacts 3FL3 in circuit with the reset coil 3r of the third floor position relay. Contacts 3FL4 in circuit with the reset coil 3D of the third landing down call relay are closed, but this down call relay will not be reset at this time because auxiliary up direction relay contacts XU6 are separated. Contacts 3FL6 and 3FL7 in circuit with lamp L3 are closed, for a purpose to be explained later.

When reset coil Zr was energized and the zone relay Z was thereby reset, it caused reclosing of contacts Z1 in circuit with coil EV of the "even" floor relay and contacts Z3 in circuit with the reset coils 4r and 2r of the "even" floor position relays. Inasmuch as contacts 2FL3 are now closed, reset coil 2r is energized to reset the second floor position relay.

As inductor 99 leaves vane 12C, "odd" contacts 36'-40' are separated de-energizing coils OD and 3FL. This has no effect on the third floor position relay as it remains latched in its operated condition. De-energization of coil OD causes opening of its holding contacts OD1 and its contacts OD2 in the circuit of reset coil Zr of the zone relay which is now in its reset position. Contacts OD3 in the call reset circuit, and contacts OD4 in the circuit of coil U of the "up" direction switch are opened without effect as coil U remains energized through closed contacts S2. Thus the car continues its upward movement, passing the third floor "down" call because the open contacts XU6 prevented the energization of reset coil SR of the starting switch.

As the car moves upward from the third landing "odd" inductor 99 coacts with vane 12D to cause closing of "odd" contacts 36'-40', but this is ineffective since the zone relay is in the reset position at this time and the car is leaving an "odd" floor.

As continued car movement brings inductor 100 into position with vane 12E, "even" floor contacts 36'-40' are closed energizing coil EV through closed contacts Z1. Contacts EV2 are closed to act as a holding circuit after the closing of contacts EV1 in the circuit of operate coil Z of the zone relay causes that coil to be energized and the zone relay to be set thereby opening contacts Z1 in the circuit of coil EV. Contacts EV3 and EV4 are closed without effect at this time. Contacts EV5 in circuit with lamp L2 are opened for a purpose to be later explained.

When the operate coil Z of the zone relay was energized by contacts EV1 closing, contacts Z2 in circuit with coil 3r closed to complete a circuit through contacts 36'-40', Z2, lines 38 and 54, closed contacts 3FL3 and reset coil 3r of the third floor position relay to cause resetting of that relay. Contacts Z3 in circuit with reset coil 4r are opened and contacts Z4 in circuit with coil OD of the "odd" floor relay are closed, both without immediate effect. Contacts Z5 in circuit with reset coil Zr of the zone relay are closed to prepare a circuit for the later resetting or unlatching of that relay. In addition, contacts Z6 and Z7 of lamps L2 and L3 are opened for a purpose which will be later explained. With continued

movement of the car, cam 102 engages the top limit switch 4L to close contacts 4L1 in circuit with coil 4FL of the fourth floor position relay. This causes separation of contacts 4FL1 in the car direction determining circuit, the closing of contacts 4FL2 preparatory to actuation of coil 3FL on the downward journey, the closing of contacts 4FL3 in the circuit of reset coil 4r to prepare a circuit for the later resetting of the fourth floor position relay. In the circuit of reset coil TC of the top floor car call relay, contacts 4FL4 are closed. Ordinarily, this would cause the starting switch to be released to its stop position by the energization of release coil SR but since contacts 4L2 of the top limit switch 4L had previously opened the circuit of coil XU of the auxiliary "up" direction relay, the starting switch has already been released by the subsequent opening of contacts XU1 in the circuit of operate coil S.

As cam 102 engaged the top limit switch 4L, contacts 4L2 also opened the circuit of coil U to de-energize that coil and cause stopping of car movement by de-energizing the hoisting motor and applying the brake in the conventional manner. Contacts U1 in the circuit of coil NT of the loading time relay are opened to cause this relay to start timing by discharging the energy stored in capacitor 32 through the coil NT. Contacts U4 are closed to energize the reset coil TC of the top floor car call relay through the circuit from the positive (+) main, contacts U4 and D4, resistance R2, lines 71 and 39, contacts 4FL4 and TC1, the reset coil TC of the top floor car call relay and lines 10C and 11 to the negative (-) main.

At this point it may be noted that, under certain circumstances, it may be desirable to initiate the stopping operation at the terminal floor in the same manner as at an intermediate floor; namely, by the separation of the inductor 100 from the top boundary of vane 12E. Such a case would be where the inductor 100 had a more critical operate point of arrival than would be the case with the cam operated limit switch 4L. In such an event, the operate coil 4FL of the fourth floor position relay would be made subject to the closing of contacts on the third floor position relay and to the closing of "even" floor contacts 36'-40' instead of merely the closing of limit contacts 4L1, as is indicated in FIGURE 3.

After the loading time operation is completed as coil NT becomes insufficiently energized to hold the relay operated, contacts NT1 close in the circuit of operate coil S and contacts NT2 close in the car direction determining circuit to complete a circuit through coil XD of the auxiliary "down" direction relay, the circuit being through contacts NT2, 3D2, lines 20a and 20b, contacts 3FL5, 3FL1, 2FL1, 1FL1, coil XD and contacts U3, XU5 and 1L2 to prepare the car for downward movement in response to the down hall call previously registered at the third floor.

Energization of auxiliary down relay causes the closing of contacts XD5 in circuit with contacts NT1 in the circuit of operate coil S of the starting switch. This switch operates to close its contacts S2 in circuit with now closed contacts XD2 in the circuit of coil D of the down direction switch. As this switch moves to its operated position, it closes its contacts to energize the hoisting motor and release the brake in the conventional manner.

Assume now that, as the car starts on its downward movement, an up hall call is registered at the second floor and an up call is registered at the first or lobby floor by intending passengers. The second floor call results in the closing of contacts 2U1 in the call reset circuit and contacts 2U2 in the car direction determining circuit (FIGURE 2), both without effect as long as the car is moving downward. In addition, contacts 2U3 in the circuit of lamp L2 (FIGURE 2) are closed to become operative as the car approaches the second floor for a purpose and in a manner which will be explained shortly.

When the up call was registered at the first or lobby floor, contacts 1U1 in the call reset circuit and contacts 1U2 in the car direction circuit were closed. These latter contacts serve to secure continued downward progress of the car until it reaches the lower terminal.

As continued downward travel causes inductor 99 to come into operating proximity to vane 12D contacts 36-40 close. The closing of these contacts completes a circuit through now closed contacts Z4 in the circuit of coil OD of the "odd" floor relay and through closed contacts XD4 and 4FL2 in the circuit of coil 3FL of the third floor position relay. As previously explained, contacts OD1 are closed to act as a self-holding circuit and contacts OD2 are closed in circuit with closed contacts Z5 to energize reset coil Zr of the zone relay. Actuation of the third floor position relay causes contacts 3FL1 in the car direction determining circuit to open without effect since the down direction is maintained by the first floor call. Contacts 3FL2 in circuit will coil 2FL are closed preparatory to the energization of this coil as the car approaches the second floor. Contacts 3FL3 in circuit with reset coil 3r are closed preparatory to resetting the third floor position relay as the car approaches the second floor. Contacts 3FL4 in the circuit of reset coil 3D are closed. Contacts 3FL5 in the car direction determining circuit are opened, and contacts 3FL6 and 3FL7 in the circuit of lamp L3 are closed—all without immediate effect at this time.

As contacts 3FL4 are closed, a circuit through contacts OD3, 3FL4, XU6, 3D1 and reset coil 3D is completed through the release coil SR of the starting switch to initiate the stopping operation. As this switch releases, it closes its contacts S3 to complete a circuit for the resetting of the third floor down hall call through contacts S3, resistance R1, contacts OD3, 3FL4, XU6, 3D1 and reset coil 3D. Simultaneously contacts S2 are separated in the circuit of coil D of the down direction switch preparatory to start of the actual stop process as inductor 99 leaves the lower edge of vane 12D. As this happens, contacts 36-40 are separated to de-energize coil OD of the "odd" floor relay. This results in the separation of contacts OD4 in circuit with coil D of the down direction switch, at which time this coil is de-energized to cause the actual stop operation, as previously described. The release of the down direction switch closes contacts D4 to complete a circuit through contacts U4, D4, resistance R2, and lines 72, 65 and 64 to reset any car call or down call for the third floor which may have been registered as or after inductor 99 separated from the lower edge of vane 12D.

After the stop at the third floor and in the manner which has been previously described, the timing of the loading time relay causes the restart of downward travel. As inductor 99 contacts the upper edge of vane 12C, "odd" contacts 36-40 are again closed, but this time without effect since there is no completed circuit through any coil in the upper half of FIGURE 3. Continued car movement brings inductor 100 into co-operative relation with vane 12B which brings about the actuation of the second floor position relay and resetting of the third floor position relay in a manner similar to that which has been previously described.

In addition, coil EV of the "even" floor relay is energized to cause the closure of contacts EV1 in circuit with coil Z of the zone relay. Actuation of this relay closes contacts Z6 in circuit with lamp L2 preparatory to illuminating this lamp. As continued car movement causes inductor 100 to separate from the lower edge of vane 12B, the circuit for coil EV is disrupted, as the contacts 36'-40' open, causing contacts EV5 in series with lamp L2 to close and resulting in the illumination of this lamp to inform the "up" passenger at the second landing that his call is registered and he is to await the return of the car.

From this explanation it will also ensue that lamp L3 will have been lighted at the third floor while the car was passing that floor to inform the

intending downward travelling passenger to await the return of the elevator car during its previously described upward travel to the top terminal. The subsequent association of inductor 100 with vane 12A has no effect. Continued car movement to the lower terminal results in the actuation of contacts 36-40 as inductor 99 coacts with vane 12 and the actuation of limit switch 1L as it encounters cam 102 with results much the same as those which were explained for the stop at the upper terminal.

From the foregoing description it will be understood that a call at any floor will be effective to stop the car at that floor so long as the inductor and co-operative vane are in operative association at that floor. Also that the registration of a call at a floor corresponding to the momentary location of the car but after separation of the vane and inductor is ineffective to cause the false stopping of the car at the next adjacent floor such as is experienced with previously known systems of this general type. This is true because of the interlocking relationship between the "odd" and "even" floor circuits and the actuation of the zone relay at "even" floors and resetting of said relay at "odd" floors.

It will be appreciated that the described arrangement provides an accurate "distance stopping" arrangement and that only a single length vane section need be stocked for various speeds of service since this vane section will be located at a greater or lesser distance with respect to the stopping position to compensate for the different speeds of the car.

The mentioned vane sections e.g. 12A, 12B are separated by a gap which amounts to substantially twice the stopping distance corresponding to that determined by the speed at which the elevator car is travelling. It is to be observed that all lower vane sections are effectively used only during upward travel of the car whereas all upper vane sections of the respective groups of vanes (for "odd" and "even" numbered floors) are effectively employed during downward car travel.

As the invention is equally useful for many different types of elevators, since in all cases it produces an accurate remote indication of the actual position of the car in its hoistway, it is to be expected that it may appear in changed formation to adapt it to a specific purpose. Thus slight variations in form may be made without departing from the spirit and scope of the invention.

What we claim is:

1. A selector arrangement for providing an accurate indication of the location of an elevator car as it traverses its hoistway from one floor to another in sequential order; comprising:

(a) switching means actuatable during travel of the car in said sequential order;

(b) said switching means including two switches each having associated therewith a group of switch actuating means;

(c) the switch actuating means of one group being mounted in the hoistway in correspondence with even numbered floors and the switch actuating means of the other group being similarly mounted in the hoistway in correspondence with odd numbered floors;

(d) each of said switches being mounted on said elevator car and being operative when the car's position brings said switch in cooperative relation with a respective one of said switch actuating means such that one of said switches is operated as the car approaches each even numbered floor and the other of said switches is operated as the car approaches each odd numbered floor;

(e) electric circuit means associated with each of said switches and effective when actuated to control the travel of said car, each said electric circuit means being alternately responsive to the actuation of its associated switch;

(f) said electric circuit means including means provid-

ing a varying indication of the floor location of the car as it traverses its hoistway.

2. A selector arrangement for providing an accurate indication of the location of an elevator car as it traverses its hoistway from one floor to another; comprising:

(a) switching means actuatable during travel of the car in said hoistway;

(b) said switching means including two switches each having associated therewith a group of switch actuating means;

(c) the switch actuating means of one group being mounted in the hoistway in correspondence with even numbered floors and the switch actuating means of the other group being similarly mounted in the hoistway in correspondence with odd numbered floors;

(d) each of said switches being mounted on said elevator car and being operative when the car's position brings said switch in cooperative relation with a respective one of said switch actuating means such that one of said switches is operated as the car approaches each even numbered floor and the other of said switches is operated as the car approaches each odd numbered floor;

(e) electric circuit means associated with each of said switches and effective when actuated to control the travel of said car, said electric circuit means being responsive to the actuation of its associated switch;

(f) said circuit means including means representing floor locations of the elevator car in accordance with the operation of said switches at even and odd floors;

(g) each of said representing means being actuated in its associated circuit means by one of said switches to thereby represent one floor location of said car.

3. An automatic elevator control system having at least

35 one elevator car for travel at a desired speed in a hoistway to respond to service demands to and from terminal landings and intermediate landings adjacent said hoistway comprising; first control means mounted in said hoistway, said first control means including a first group of elements

40 comprising two spaced elements mounted to correspond with each even numbered intermediate landing and a second group of elements comprising two spaced elements mounted to correspond with each odd numbered intermediate landing; said two spaced elements corresponding

45 with each intermediate landing being so disposed that the space between them is substantially equal to twice the stopping distance of the car traveling at said desired speed; second control means including two switches mounted on said car, each one of said switches being operative

50 when the travel of the car brings it into cooperative relation with one of said groups of elements so that one switch is operative at even numbered intermediate landings and the other is operative at odd numbered intermediate landings; and circuit means operatively connected to said second control means for controlling the response of said elevator car to service demands.

4. An automatic elevator control system having at least one elevator car for travel at a desired speed in a hoistway to respond to service demands to and from terminal

60 landings and intermediate landings adjacent said hoistway comprising; induction switch actuating vanes mounted in said hoistway corresponding to each intermediate landing, two said vanes having a space therebetween being mounted in correspondence with each said intermediate landing, said space between each said two vanes being substantially equal to twice the stopping distance of the car traveling at said desired speed; inductor switch means mounted on said car actuatable when the travel of said car brings said switch means into cooperative relation

65 with said vanes; said vanes corresponding to said intermediate landings and said inductor switch means being so disposed in relation to each other that as the car approaches each intermediate landing said switch means are first actuated and then deactivated before the car arrives at each landing; and circuit means operatively connected

to said inductor switch means and responsive thereto so that upon the actuation of said inductor switch means said circuit means operates to represent the location of the car as having arrived at a landing and upon the deactuation of said inductor switch means said circuit means operates to initiate the stopping sequence of the car provided the car is responding to a service demand at said landing represented as having been arrived at.

5. An automatic elevator control system having at least one elevator car for travel at a desired speed in a hoistway to respond to service demands to and from terminal landings and intermediate landings adjacent said hoistway comprising; vane means mounted in said hoistway, said vane means including a first group of vertically aligned vanes comprising two spaced vanes mounted in correspondence with each even numbered landing and a second group of vertically aligned vanes comprising two spaced vanes mounted in correspondence with each odd numbered intermediate landing; said first group being in one vertical plane and said second group being in another vertical plane, said vertical planes being parallel to each other; said two spaced vanes in correspondence with each intermediate landing being so disposed that the space between them is substantially equal to twice the stopping distance of the car traveling at said desired speed; two magnetic inductor switches mounted adjacent each other on said car, and in position for cooperative actuation with said columns of vanes respectively such that one switch is operative at even numbered landings and the other switch is operative at odd numbered landings; said vanes and said inductor switches being so disposed in relation to each other that as the car approaches each intermediate landing the corresponding inductor switch is first actuated and then deactuated before the car arrives at the landing; and circuit means operatively connected to said inductor switches and responsive thereto so that upon the actuation of said corresponding inductor switch said circuit means first operates to represent the location of the car as having arrived at the landing and upon the deactuation of said corresponding inductor switch said circuit means operates to initiate the stopping sequence of the car provided the car is responding to a service demand at the landing being approached.

6. A selector arrangement according to claim 1, wherein said switching means and said associated circuit means are so interconnected that during car travel one of said electric circuit means associated with one of said switches is prevented being reactivated until the other electric circuit means associated with the other switch has been actuated by its corresponding switching means, thereby to prevent the car stopping at a succeeding floor in response to a call for a preceding floor being in registration.

7. A selector arrangement according to claim 2, wherein in said two switches are magnetic inductor switches, and said actuating means are in the form of vane means.

8. A selector arrangement according to claim 7, wherein in said vane means include pairs of spaced apart vane sections of substantially equal length, the pairs of vane sections corresponding to odd numbered floors being aligned, and the pairs of vane sections corresponding to even numbered floors being aligned, said aligned vane sections corresponding to odd numbered floors being disposed in staggered relation to the aligned vane sections corresponding to even numbered floors.

9. A selector arrangement for providing an accurate indication of the location of an elevator car as it traverses its hoistway; including switching means actuated by movement of the car in the hoistway, said switching means comprising two spaced apart magnetic inductor switches mounted on the elevator car and two groups of vane means located in the hoistway, one group of vane means corresponding to even numbered floors and being adapted to actuate one inductor switch, the other group of vane means corresponding to odd numbered floors and being adapted to actuate the other inductor switch, first and

5 second electrical circuit means including even floor relay means, odd floor relay means, and zone relay means having set coil means and reset coil means, said even floor relay means and said set coil means being connectable through said one inductor switch in said first circuit means, said odd floor relay means and said reset coil means being connectable through said other inductor switch in said second circuit means, said switching means and said first and second circuit means being so interconnected that during car movement said first circuit means associated with said one inductor switch is prevented being reactivated until the second circuit means associated with the other inductor switch has been actuated by its corresponding switching means and said zone relay means has been reset through said reset coil means in said second circuit means, which latter circuit means is prevented being reactivated until the first circuit means has been actuated and said zone relay means has been set again through said set coil means in said first circuit means, whereby a call registered for a preceding floor will be prevented causing the car to stop at a succeeding floor.

11. A selector arrangement for providing an accurate indication of the location of an elevator car as it traverses its hoistway in response to service demands; including switching means actuated by movement of the car in the hoistway, said switching means comprising two spaced apart magnetic inductor switches mounted in side-by-side relation on the elevator car and two groups of spaced apart and paired vane means located in the hoistway, corresponding to the floor, and adapted to actuate said switches, respectively, each pair of vane means including two aligned vane sections with a gap therebetween, one inductor switch being effectively actuatable by a respective one of said two vane sections corresponding to each even numbered floor, the other inductor switch being effectively actuatable by a respective one of said two vane

13

sections corresponding to each odd numbered floor, said pairs of vane sections corresponding to even numbered floors being disposed in staggered relation to the pairs of vane sections corresponding to the odd numbered floors, a plurality of electrical circuit means including even floor relay means, odd floor relay means, and zone relay means having set coil means and reset coil means, said even floor relay means and said set coil means being operatively connected in one of said circuit means, said odd floor relay means and said reset coil means being operatively connected in another of said circuit means, 10 said switching means and said electrical circuit means being so interconnected that during car movement said one circuit means associated with said one inductor switch is prevented being reactuated until the other circuit means associated with the other inductor switch has been actuated by its corresponding switching means and said zone relay means has been reset through said reset coil means in said other circuit means, which latter circuit means is prevented being reactuated until the one circuit means has been actuated and said zone relay means has been set by said set coil means in said one circuit means.

12. In an elevator installation having a hoistway, a plurality of landings connected to said hoistway, an elevator car having a platform and operable in said hoistway to travel therein to answer service demands to and from said landings, first and second co-operable control means located on said car and in said hoistway, respectively, to position said car with respect to said landings during operation of said car in said hoistway, and electric circuit means including respective switch means in said circuit means operatively connected to said first control means; comprising in combination:

- (a) at least one pair of inductor switch means forming said first control means and mounted in spaced apart relation to each other on said car;
  - (b) and a plurality of paired vane means forming said second control means, each pair of vane means having a gap therebetween and being arranged for location corresponding to a landing, so that each vane means of a pair is about equidistantly spaced from the co-operating inductor switch means, when the latter is located in the gap between said pair and the car platform is level with the respective landing;
  - (c) said paired vane means being distributed with respect to each other in two groups corresponding to respective odd and even numbered landings, with pairs of vane means corresponding to odd numbered landings aligned with each other, and pairs of vane means corresponding to even numbered landings aligned with each other and arranged in alternate relation to aligned pairs of vane means corresponding to odd numbered landings;
  - (d) one of said inductor switch means being located for co-operation with pairs of vane means corresponding to even numbered landings, the other inductor switch means being located for co-operation with pairs of vane means corresponding to odd numbered landings so that said inductor switch means through co-operation with respective pairs of vane means operate said switch means in respective circuit means during travel of said car to thereby control the movement of the latter with respect to odd and even landings.
13. In an elevator system according to claim 12, wherein

- (a) said pairs of vane means corresponding to respective odd and even numbered landings are disposed in the hoistway so that vane means for even numbered landings are vertically spaced from each other in aligned relation and are staggered with respect to the vane means for odd numbered landings which are also vertically spaced from each other in aligned relation; and
- (b) said circuit means include first contact means for use in a signaling circuit operatively connectable in said circuit means when a service demand for a

65
70
75

14

landing occurs during location and movement of one of said inductor switch means in the gap between the pair of vane means at said landing.

14. In an elevator system according to claim 13, including
- (a) respective floor position switch means for odd and even landings in said circuit means, said floor position switch means being of the set and reset type;
  - (b) second contact means in said circuit means operable by coaction of said inductor switch means with co-operating vane means for setting floor switch means co-ordinated with succeeding floor landings and simultaneously for resetting floor switch means co-ordinated with preceding floor landings during movement of said car through said hoistway; and
  - (c) means for making ineffective a service demand as soon as the respective inductor switch means becomes disengaged from a predetermined one of said pair of vane means.
20. 15. In an elevator control system having vane means in the hoistway and inductor switch means on the elevator car, which is adapted to travel in the hoistway to answer a service demand to or from a floor; control circuit means including respective first and second contact means 25 and floor position relay means for odd and even numbered floors, some of said vane means being grouped in aligned pairs corresponding to odd numbered floors and even numbered floors, pairs of vane means corresponding to odd numbered floors being spaced from and disposed in 30 staggered relation to pairs of vane means corresponding to even numbered floors, each pair of said vane means being provided with two spaced apart vane sections substantially equidistantly located at either side of the associated inductor switch means when the car is at the level 35 of its respective floor, said inductor switch means being spaced from each other on said car and in registry with associated pairs of vane means corresponding to odd and even numbered floors, so that one of said inductor switch means coacts with vane means corresponding to odd floors 40 and the other of said inductor switch means coacts with vane means corresponding to even floors, said control circuit means being operable via said first or second contact means, which are operatively connected to said one and said other inductor switch means, respectively, said first contact means conditioning said circuit means for 45 causing energization of position relay means for odd floors and said second contact means conditioning said circuit means for energization of position relay means for even floors, whereby positive floor indication is attained and sequential floor stepping operations are achieved, and 50 means operatively connected with said circuit means for resetting even floor position relays at odd floors and odd floor position relays at even floors.
16. In an elevator control system having an elevator car with a platform and with magnetically operable inductor switch means mounted on said car, groups of vane means located in the hoistway and arranged for coaction with said inductor switch means, when said car travels to and from floors to answer a service demand at one of said floors along said hoistway in either direction thereof; 55 comprising in combination:
- (a) one group of said vane means being located as aligned and paired vane sections and being co-ordinated to odd numbered floors, another group of said vane means being disposed in aligned and paired vane sections and being co-ordinated to even numbered floors, said vane sections co-ordinated to said odd numbered floors being arranged in spaced and staggered relation to said vane sections co-ordinated to said even numbered floors;
  - (b) said inductor switch means including one located for registry with said vane sections co-ordinated to said odd numbered floors and one located for registry with said vane section co-ordinated to said even numbered floors;

- (c) a respective one of each pair of vane sections depending on the direction of travel of the car being determinative of corresponding floor stepping switch operations caused by the coaction of said inductor switch means with said respective one vane section; and
- (d) electric circuit means including odd and even floor relay means, and respective floor position relay means operatively connected to said inductor switch means for setting car travel in a predetermined direc-

tion in said hoistway and for stopping said car at pre-selected odd or even floors in answer to service demands.
